UNITED STATES PATENT OFFICE.

GLENN H. BOLUS, OF MANSFIELD, OHIO, ASSIGNOR TO THE OHIO BRASS COMPANY, OF MANSFIELD, OHIO, A CORPORATION OF NEW JERSEY.

SUSPENSION-CLAMP.

1,073,658.

Specification of Letters Patent. Patented Sept. 23, 1913.

Application filed August 20, 1910. Serial No. 578,221.

To all whom it may concern:

Be it known that I, GLENN H. BOLUS, a citizen of the United States, residing at Mansfield, in the county of Richland and State of Ohio, have invented certain new and useful Improvements in Suspension-Clamps, of which the following is a specification.

This invention relates to suspension clamps, and has for its primary object to provide an improved device of this character whereby a cable or other conductor is held against accidental displacement therefrom before said conductor has been rigidly clamped in position.

Another object is to provide an improved suspension clamp having a movable clamping member and adapted to have the conductor or cable installed in position without detaching the movable clamp therefrom.

Other and further objects will appear in the specification and be specifically pointed out in the claims, reference being had to the accompanying drawings exemplifying the invention, and in which—

Figure 1 is a side elevation of a suspension clamp constructed in accordance with this invention, and showing a conductor cable in position therein. Fig. 2 is an end elevation of the clamp shown in Fig. 1. Fig. 3 is a top plan view of the same. Fig. 4 is a section on the line IV—IV Fig. 1. Fig. 5 is a vertical longitudinal section of a modification of the invention. Fig. 6 is a section on the line VI—VI, Fig. 5. Fig. 7 is a section on the line VII—VII, Fig. 5. Fig. 8 is a detail section corresponding to Fig. 7, showing a further modification of the suspension clamp.

In the embodiment shown in the drawings, the clamping device comprises a main body member, a movable clamping member, and means interengaging between said members whereby they may be drawn into clamping engagement with a cable or other conductor 1. The main body member is preferably constructed as an integral casting comprising a pair of oppositely opening hooks or grooved saddles 2, 3, elongated longitudinally of the cable or conductor 1 to provide an extended bearing surface for said conductor. The shanks 4 and 5 of said hooks or saddles 2 and 3 are disposed respectively on opposite sides of the conductor 1 in such manner as to provide a

mousing, each for the other, as shown most clearly in Fig. 3. Thus the conductor 1 when elevated above the upper edge of the lip 6 of the grooved saddle or hook 2, would be held against lateral displacement therefrom by means of the shank 5 of the other hook or saddle. Each of the hooks or saddles is provided with a groove of substantially the same curvature or formation as the conductor or cable carried thereby, the outer ends of said saddles being deflected downwardly respectively as shown at 7 and 8 in Fig. 1. The main body casting is provided intermediately of the saddles 2 and 3 with a vertical slot 9, which permits said main body member to be introduced over the cable or conductor 1 in a plane transverse thereto until the upper edges of the lips 6 and 10 of the saddles 2 and 3 are below said cable 1, when the body member may be rotated about an axis transverse to the cable 1 until the lateral faces of the shanks 4 and 5 abut against the cable 1, when said body portion may be lifted to cause the cable to seat within the grooved saddles, as shown in Figs. 1 and 2.

In order to provide suitable means for movably supporting the main body of the clamp in such a manner that it may be oscillated about an axis transverse to the cable 1, the upper end of the body casting is provided with a globular head 11 provided with a socket 12 for the reception of the flattened circular lead 13 of an insulating pin 14, the upper wall of the globular portion 11 being perforated at 15 for the reception of the pin 14. The perforation 15 is extended to connect with an opening 16 in the lateral wall of the globular portion 11, said opening 16 being sufficiently large to permit the introduction of the flattened head 13 of the pin 14. In order to hold the flattened head 13 against displacement from its socket, a cotter pin 17 is introduced through a perforation in the globular portion 11 to hold it in its raised position, as shown in Figs. 1 and 2.

Means for clamping the cable or conductor 1 to the saddles 2 and 3 is provided by the clamp bar 18, which is slidably mounted between the shanks 4 and 5, said clamp bar being provided on its lower edge, as shown in Fig. 4, with a circular groove 19. Said block is, moreover, preferably provided with a downwardly protruding

portion 19^a opposite the slot 9, so that when the block 18 is drawn down upon the conductor 1, it is depressed, as shown in Fig. 1, so as to secure it more firmly within the suspension clamp. In order to provide means for drawing down the block 18 upon the conductor 1, it is provided with a pair of perforations for the reception of bolts 20 and 21, said bolts being preferably bent at right angles, as shown best in Fig. 4, to enable the shanks of the bolts to be housed in recesses 22, 23, formed in the walls of the shank portions 4 and 5 respectively. A pair of nuts 24 upon the lower threaded ends of the bolts 20 and 21 serve to draw the clamping block 18 into clamping engagement with the conductor 1.

Referring now to the embodiment shown in Figs. 5, 6 and 7, the main body casting of the suspension clamp is similar to the embodiment shown in Figs. 1 to 4 inclusive, with the exception that said casting is provided with a slotted head 25, the slot 26 in which is adapted to receive a tongue 27 at the lower end of a depending suspension link or bar 28 which may be supported from above in any desired or suitable manner. The tongue and slot connection between the slotted head 25 and the bar and link 28 is completed by a pin 29 which pivotally supports the suspension clamp from said bar or link.

As shown in Fig. 7, the clamping bar 18' is beveled along its upper edge at 30 to provide an abutting surface for the bolt heads 31 of the bent clamping bolts 20'.

According to the embodiment illustrated in Fig. 8 the clamping bolts are perfectly straight and the hook-shank portions of the body casting are provided with bolt sockets 32 which project laterally from the body casting, the end walls of said sockets being perforated for receiving the bolts. For this embodiment, the clamp bar 18'' is beveled more sharply above but in other respects is substantially the same as the clamp bars shown in the other embodiments.

What I claim is:—

1. In a suspension clamp, the combination with a pair of hooks opening in opposite directions with a space therebetween to permit the introduction of a conductor, of means for movably suspending said hooks to adapt them to be rotated into position supporting said conductor, said hooks being rigidly connected together in a manner to adapt each to form a mousing for the other, and means adapted to clamp the conductor to said hooks.

2. In a suspension clamp, the combination with a pair of integrally connected hooks disposed with their bills in opposite directions to adapt each to form a mousing for the other and having a slot separating the hooks, of means slidably engaging said

hooks for clamping a conductor thereto, and means for swingingly suspending said hooks whereby they are adapted to be rotated into supporting engagement with the conductor.

3. In a suspension clamp, the combination with two integrally formed hooks, the shank of one hook being in alinement with the bill of the other hook, of a clamp slideable along the shanks of said hooks upon the conductor and adapted to clamp a conductor therein.

4. In a suspension clamp, the combination with a conductor, of a pair of rigidly united hooks having their shanks disposed on opposite sides of the conductor with the bill of each hook on the same side as the shank of the other hook and with a slot between the hooks separating the shanks to a point above the end of the hooks, of a clamp interposed between and slidably engaging said shanks, and means for moving said clamp into and out of clamping engagement with the conductor, said means being adapted to retain the clamp against displacement at all times.

5. The combination with a conductor, of a suspension clamp therefor, comprising a pair of integrally formed hooks with shanks on opposite sides of the conductor to adapt each to form a mousing for the other, each of said hooks being provided between the shank and bill thereof with a saddle for the conductor, a clamp block movable up and down and slideable between the shanks of said hooks into and out of clamping engagement with the conductor, and means for pivotally suspending the clamp to swing about an axis transverse to said conductor, and means to force the clamp block against a conductor.

6. The combination with a conductor, of a suspension clamp therefor comprising two hooks in supporting engagement with the conductor, the shanks of said hooks being disposed on opposite sides of the conductor and each forming a mousing for the other hook, said hooks being spaced apart longitudinally of the conductor, a clamping block extending through said hooks above the conductor, and means interengaging between said hooks and clamp block for drawing the latter down upon the conductor, said means comprising a bolt extending through the shank of each hook with its head engaging the clamping block, and a nut movable on the bolt to engage the under side of the hook to hold the bolt and block in position.

7. The combination with a conductor, of a suspension clamp having an integral support comprising shanks on opposite sides of the conductor, said shanks being provided each with a grooved saddle for the support of the conductor and adapted respectively to form a mousing for the other grooved

- saddle, a clamp block slidably mounted on said shanks, said support being pivotally mounted and provided with a slot between said saddles to permit the support to 5 straddle the conductor and to be swung on its pivot to dispose the conductor in said slotted saddles, and separate means on opposite sides of the conductor to clamp the block against the conductor.
- 10 8. In a suspension clamp, the combination with a suspension member comprising depending hook-shaped portions separated by a slot greater in width than the conductor to be supported, the hooks being disposed 15 in opposite direction with the shank of the hook in alinement with the bill of the other and the shank of each hook being increased in width to form a grooved saddle of great width having a downwardly deflected end, 20 a clamping block slidable between the hooks and movable up and down, the upper edge of the block being beveled in an opposite direction on each side of the center, clamping bolts adapted to be inserted through 25 the wall of each hook shank having a head at one end to engage the beveled surface of the block, and a nut to bind the bolt and block in position against the conductor.
9. In a suspension clamp, the combination with a pair of integrally formed hooks 30 disposed with their bills in opposite directions having a slot between them, of means for swingingly suspending the hooks whereby a conductor may be inserted in the slot and the hooks rotated into supporting engagement with the conductor, a clamping block movable between the shanks of the hooks having a rounded portion on its under surface substantially the length of the slot, and means to press the clamping block down- 35 wardly in engagement with a conductor to be clamped whereby the conductor is bent by the said rounded portion.
- In testimony whereof I have signed my name to this specification, in the presence of 40 two subscribing witnesses, on this 16 day of 45 August, A. D. 1910.

GLENN H. BOLUS.
